UNITED STATES PATENT OFFICE.

JOSEPH C. HAWLEY, OF DUNCANNON, PENNSYLVANIA.

FOLDER AND LINER FOR SHIRT-CENTERS.

1,287,011.

Specification of Letters Patent. Patented Dec. 10, 1918.

Application filed January 27, 1913. Serial No. 744,298.

To all whom it may concern:

Be it known that I, JOSEPH C. HAWLEY, a citizen of the United States, residing at Duncannon, in the county of Perry and State of Pennsylvania, have invented a certain new and useful Folder and Liner for Shirt-Centers, of which the following is a specification.

The purpose of my invention is to place linings within shirt centers, preferably inserting a lining having a width equal to the full width of the space within the center, and, where desired, to feed the centers and linings to a sewing machine.

15 A further purpose of my invention is to automatically overlap a shirt center about a lining.

20 A further purpose of my invention is to arch a lining for the purpose of reducing the extreme distance between its edges while introducing it within a shirt center or in other location.

25 A further purpose of my invention is to spread a shirt center as it leaves the folder in its feed toward the machine needles.

30 A further purpose of my invention is to make the interior of a folder and of a lining placing mechanism within it accessible for regulation of the placing and feed of the fabrics therein.

Further purposes of my invention will appear in the specification and claims thereof.

I have preferred to illustrate my invention by two forms thereof which have been 35 successfully used by me, which have proved to be simple, inexpensive and highly efficient and which at the same time well illustrate the principles of my invention.

Figure 1 is a front elevation of the preferred form of my invention.

Fig. 2 is a section of the structure shown in Fig. 3, upon line 3—3 thereof.

Fig. 3 is a top plan view of the structure shown in Fig. 1.

45 Fig. 4 is an enlarged section of the structure shown in Fig. 3 upon line 4—4 thereof.

Fig. 5 is a broken end view of a second form of my invention.

50 Fig. 6 is a longitudinal section taken upon the line 6—6 of Fig. 5.

Fig. 7 is a section upon line 7—7 of the structure shown in Fig. 6, omitting the bracket support.

55 In the manufacture of shirts, particularly negligée shirts, it is customary to apply a decoration or facing upon one edge of the

shirt where it is cut at the center and this facing is technically called a shirt "center."

My invention finds such excellent illustration in its application to folding, applying and lining shirt centers that I have preferred to describe it and claim it in terms of shirts and centers, notwithstanding that I recognize its usefulness in folding, applying and lining other fabric facings, backings or strips and believe that such other uses of the principles of my invention are within the scope of this application. I, therefore, use the shirt and center terms as emblematic or representative of any flexible parts which require folding and lining, or either of these within the spirit and scope of my invention.

Because of the difficulty of properly inserting linings within shirt centers and other folded facings, edgings and backings, this work has been performed by hand. My invention contemplates the folding of the part, herein called a shirt center and the proper insertion of a lining within the center, all ready to place upon the shirt, whether the center, with or without a lining, be fed to the needles of a machine separately or in conjunction with the garment, herein called the shirt with which it is thereby connected.

My invention is shown in the most convenient form, as an attachment for a sewing machine, adapted to feed the center directly to the needles of a sewing machine, of which one application is illustrated in the copending application for shirt centering device filed jointly by me and by William Steel Jackson and in which four needles are shown as representative of any required or desired number or arrangement of needles required for the several seams to be made, whether these seams be decorative or required to unite the fabrics. The fourth would not ordinarily be used unless the center were being placed upon the shirt at the one operation.

In order that my center lining mechanism may be properly supported in front of any suitable needles, I provide a bracket having base 22, end 23, top 24 and rearwardly extending support 25.

I will describe first my preferred form shown in Figs. 1—4. My lining device 26 is shown as supported at an angle, best seen in Fig. 1, so that the center, inclosing a lining where desired, comes out of the folder at 27 and having its preferably overlapping

edges upon the side 28, here shown as the bottom of the folder. It may be fed directly beneath the presser foot where the center is sewed without attaching it to the shirt.

5 This action takes place whether the center be lined or not.

Where the center and shirt are not attached during the sewing operation upon the center, with or without inclosure of lining 10 therein, it is customary to omit one row of stitches from the center, placing this seam when the parts are attached.

Omitting, for the present, consideration of the inclosed structure by which the lining is 15 fed and properly placed, I will first describe the folder for the center which surrounds it. This consists of the outer casing 29, slotted at 30, to permit access to the fabric from the top throughout the greater part of the folder length, so that the feed may be accelerated by hand and any stoppage corrected in that way, having under side 31, joined to the upper side by curved edges 32. In both of the forms shown, the outer as well as the inner 25 sides of this folder are tapered quite appreciably, except, preferably, for a short distance near to the front and from, say, point 33, as best seen in Figs. 1 and 3.

The outer casing surrounds an inner casing of approximately the same shape and of nearly enough the same size in outside dimensions, as compared with the inside of the outer casing, so as to provide a shallow passage way 34 between them of about the 30 same depth, across the fabric. The word "depth" is here used to indicate the distance across the passage between its inner and outer walls as measured perpendicularly to these walls. At the outer or rear 35 end, because of the taper, the perimeter of this passage is much longer than that at the forward end, with the result that the fabric being folded does not have its edges in contact at the rear end, where the strip from 40 which the center is formed is introduced, though these edges are designed, in the illustrations, to overlap at the forward or delivery end to any desired extent. The position of the overlapped edges may be predetermined to bring it in the middle or at 45 either side of the center width.

I unite the inner and outer casings, as at 50 35, thereby interrupting the perimetrical continuity of the passages 34, uniting them 55 at the rear end where the fabric enters and where its edges have not been turned toward each other sufficiently to require this space.

It is not necessary to unite the casings for 55 any considerable length of the folder, in 60 order to support the one from the other. The passage is therefore made continuous perimetrical at the lower or inner end of my device so that the edges of the cloth 65 36, 37 forming the shirt center, may not only meet but there pass at any designed point

38, (Fig. 4) in the folder width, with the result that the fabric edges are completely closed and overlap, so that a row of stitches may be formed through them by a needle appropriately placed. 70

The inner member, as so far described, forms a spreader or form, merely, to set the inner boundary of the folder passage within the outer casing. It performs another function, however, which is one of the main 75 features of my invention. It is made hollow throughout its length to provide passage 39 for the fabric 40 forming a lining for the center.

The lower part of passage 39, as well as 80 the lower part 34², of the passage 34, is bowed or curved in cross section for a purpose more fully pointed out later. In the other form illustrated these lower parts are straight in cross section. 85

In order that the lining within the passage 39 may be straightened out whenever it kinks or becomes misplaced, I provide a slot 41 in that wall, 42, which is shown as forming at the same time the lower wall of 90 the passage 34 and the upper wall of the passage 39 throughout the major parts of the lengths of these passages.

In order that the lining 40 may be fed within the passage 39 selectively, without 95 difficulty, I have extended the bottom of this passage, in effect, as at 43, permitting the lining to be rested on this extension and fed directly in therefrom.

Where the lower part, *i. e.*, the discharge 100 part, of the lining passage has straight sides in cross section, it is difficult to feed a lining of sufficient width through the passage, as the connecting walls at the sides limit the spread of the lining and are themselves 105 closer together than the inside width of the shirt center, which surrounds them.

In order to more fully fill the center width I prefer to use the construction shown best in Fig. 4 where the curvature of the lower 110 part of the discharge end of the passage 39 at 39² permits me to use a lining having the same width or a width even somewhat wider than the width of the straight (upper) part of the discharge end of this passage 39. The 115 width of this straight discharge part of passage 39, largely determines and very nearly agrees with the ultimate interior width of the folded center since the greater contour of the curved part increases the extent of overlap of the fabric edges rather than the width of the folded center. The curvature of the lining, however, results in corresponding increase in the lining width when it is straightened out. The curvature has been 120 exaggerated in Fig. 4.

It will thus be seen that I can fill the interior width of the center by the lining to any predetermined extent desired and can even feed into the center a lining which is 125 130

wider than the interior center width where any utility for this exists, using a relatively stiff lining as a spreader if desired since it need not be folded at all, only curved 5 slightly.

The form shown in Figs. 5, 6 and 7 is intended to be identical with that shown in Figs. 1 to 4 except for the contour of the lower part, *i. e.*, the discharge end of the 10 passages and their limiting walls. The parts 29', 32', 34', and 39' are therefore like the correspondingly numbered parts without the primes in Figs. 1 to 4, except as to the changes required at the discharge end incident 15 to making the rear portions of the shirt center and lining passages straight in cross section as best seen in Fig. 7.

In both forms shown by me the taper of the structure desirable for the folding function results in the lining not requiring the full width available for the inner casing at the rear end of the folder. It can, of course, be given the full width if desired but in Fig. 3 I show that I may spread the center at 25 the front end as by wings 46, 47 which may form part of the plate 48, and that I may form the feed tube for the lining as of the intended lining width throughout its length, whether it be straight or curved in cross section or, as shown, part straight and part curved.

In this way I provide an outer folder for the shirt centers which overlaps them upon the under side in the form shown to any 35 desired extent and at any position from side to side of the structure which may be desired. The shifting of this point from side to side to produce the overlap upon the right or left to any desired degree, or at the center, is a matter of convenience only, as is also the determination of which edge shall lie outside the other, where this makes any difference.

Within the outer folder for the shirt center, I place a guide for the lining, which 45 feeds the lining with absolute fidelity within the folded shirt center, filling the width to any extent desired and illustrated by me as filling substantially the entire width, or 50 the entire width with such crowding as may be wished, according to the desire of the designer in view of my disclosure herein. The width filled depends upon the width of channel provided at 39', the width of the 55 lining itself with respect to the center width, and the amount of curvature which may be given, as in Fig. 4.

When the shirt center emerges from the 60 folder, it may be spread by suitably mounted supporting edges, as seen at 49 and 50, with the result that the center is fully stretched to the intended internal width, insuring ample room and full seating for the lining, forming a particularly neat, firm and smooth lined center. It is adapted to be

fed directly under the presser foot of a sewing machine and sewed in this condition without attachment to a shirt and I have successfully used it in this way.

For structural reasons I have preferred to 70 show the upper covering of the lining space as double, comprising the edges 61 and 62 and the plate 48 uniting them and filling out the required width for the inner member, limiting the outer passage through the most 75 of the tapered part of its length.

Having thus described my invention, what I claim as new and desire to secure by Letters Patent is:—

1. In a device of the character stated, 80 outer and inner walls tapering longitudinally and providing a fabric passage therebetween, whose cross section at the discharge end is approximately straight where the middle of the fabric passes, in combination 85 with walls forming a lining passage extending longitudinally of the first passage and walls and arched in its transverse section at the discharge end, with the edges of the arch located at the approximate ends of the 90 straight section of the first passage and having the concave side of the arch facing said straight section of the first passage.

2. In a device of the character stated, 95 outer and inner walls forming a passage characterized in cross section at the discharge end by an approximately straight portion where the middle of the fabric passes and having the remainder of the passage curved, in combination with walls 100 forming a lining passage characterized in cross section at the discharge end by a curved contour corresponding generally to the contour of the adjoining part of the first passage and having the concave side of 105 the curve facing the straight portion of the first passage.

3. In a device of the character stated, 110 outer and inner walls forming a passage characterized in cross section at the discharge end by an extended relatively straight portion on one side, the passage being reversely turned adjoining the straight portion at each end thereof, in combination with a wall forming a lining passage between it and the inner wall, said lining passage at the discharge end conforming substantially to the contour of the reversely turned portions of the first passage.

4. In a device of the character stated, 120 a longitudinally tapered fabric folder characterized in the cross section of the fabric passage at the discharge end by a considerable straight portion, in combination with a lining guide providing a passage for a lining 125 which is curved in cross section at the discharge end, the chord of the curve paralleling the straight portion of the fabric passage.

5. In a device of the character stated, 130

- outer and inner walls, longitudinally tapered and at the discharge end in transverse section approximately straight for a considerable portion of the passage and re-
 5 versely turned at the ends of the straight part, forming, opposite said straight portion, a portion of the fabric passage of arched transverse section, in combination with an inclosed lining guide arched in
 10 transverse section near the discharge end, with the concave side of the arch facing the straight portion of the passage, and a spreader for the fabric at approximately the point of discharge of the lining from the
 15 lining guide.
6. In a device of the character stated, an outer casing having one side tapered and of approximately straight cross section throughout the greater part of its length
 20 and another side curved in cross section at the discharge end, in combination with an inner casing conforming substantially to the shape of the outer casing and forming a fabric passage therebetween and a wall inside
 25 the inner casing, of curved cross section at the discharge end and providing a curved lining passage between it and the inner casing.

7. In a device of the character stated, an outer casing having one side approximately straight in cross section, tapered through-
 30

out the greater part of its length and straight the remainder of its length and the opposite side straight in cross section part of its length and curved in cross section at 35 the discharge end, in combination with an inner casing conforming substantially to the shape of the outer casing to provide a fold-guiding passage therebetween and walls forming an interior lining passage within 40 the casing of substantially uniform effective width for the greater part of its length.

8. In a device of the character stated, outer and inner walls tapering longitudinally, of approximately straight transverse 45 section on one side at the discharge end and reversely turned at the ends of the straight section to provide a folding passage for a fabric between the walls, walls forming a space of greater length in transverse sec- 50 tion at the discharge end of the first walls than the distance between the terminals of the straight section, to receive a lining, and a spreader in proximity to the edges of the approximately straight side at the point of 55 delivery of the lining to spread the folded fabric for the purpose of receiving the lining.
